UNITED STATES PATENT OFFICE.

ROLLIN ABELL, OF MILTON, MASSACHUSETTS.

INTERNAL-COMBUSTION ENGINE.

Application filed November 6, 1919. Serial No. 336,155.

To all whom it may concern:

Be it known that I, ROLLIN ABELL, a citizen of the United States, and a resident of Milton, county of Norfolk, and State of Massachusetts, have invented certain new and useful Improvements in Internal-Combustion Engines, of which the following is a full, clear, concise, and exact description, such as will enable others skilled in the art 10 to which the invention relates to make and use the same, reference being made therein to the accompanying drawings, which form a part of this specification.

My invention relates to internal combustion engines, and particularly to the construction and arrangement of the valves and elements associated therewith for controlling the supply of combustible mixture to the cylinder of the engine, and the exhaust there- 20 from of the gases resulting from the burning of the combustion mixture within the engine cylinder.

More specifically stated, my invention relates to internal combustion engines of the 25 four stroke single poppet valve type wherein the combustible mixture flows into and the burned gases flow from the cylinder through a single port controlled by a single positively opened poppet valve, and in 30 which a distributing valve is provided for directing the inflowing combustible mixture from the usual inlet or supply conduit toward the port aforesaid and for directing the outflowing exhaust gases from said port 35 into the exhaust conduit of the engine; such, for example, as is shown in my United States Patent for internal combustion engine, No. 1,311,200, July 29, 1919.

The object of my invention is to reduce to 40 as great an extent as possible the waste of combustible mixture heretofore met with in internal combustion engines of the four stroke single poppet valve type above referred to. Thus in the present form of four 45 cycle single poppet valve engines there is ordinarily a passage or chamber of considerable volume between the distributing valve and the combined inlet and outlet port which is closed by the poppet valve, and which pas- 50 sage or chamber is left full of combustible mixture at the termination of the suction stroke. Afterward and when the said port is placed in communication with the exhaust passage or conduit by the distributing valve, 55 and when the poppet valve is opened, the burned gases flowing from the cylinder will

push the combustible mixture present in the chamber referred to out from said passage and into the exhaust conduit, thus wasting a considerable amount of combustible mixture each cycle of operation of the engine. 60 This waste of combustible mixture is obviously the greater the greater the total volume of the passage, chamber, or space through which both the combustible mixture and the 65 exhaust gas flows, and is of such a magnitude as to result in serious loss of efficiency even in engines designed with special reference to reducing the volume of such common passage as much as possible.

As stated the principal object of my invention is to reduce the loss of efficiency due to the wasting of combustible mixture trapped in the common supply and discharge passage immediately beyond the single valve 70 past which both the inflow and outflow of the gases in question takes place in engines of the type referred to; and a further object of my invention is to provide improved 75 valve mechanism for use with internal combustion engines of the four cycle single poppet valve type for controlling the flow of combustible mixture to and the exhaust of the burned gases from the cylinder of the engine.

With the above and other objects of invention in view, my invention consists in the improvements in and relating to internal combustion engines illustrated in the accompanying drawings and hereinafter described and claimed; and in such variations and modifications thereof, within the scope of the concluding claims, as will be obvious to those skilled in the art to which my invention relates.

In the drawings wherein the preferred embodiment of my invention is illustrated:

Figures 1, 2, 3 and 4 are sectional views showing the upper end of the cylinder, and the valve mechanism of an internal combustion engine in which my invention is present, the several views showing the positions of the various parts corresponding with the four principal phases of the cycle of operation of the engine.

Figure 5 is a view in section for the most part, and in which the engine is shown in side elevation.

Figure 6 is a view employed to illustrate the operation of my invention.

Referring now to the drawings, the reference numerals 10 designate the cylinders of

- a multiple cylinder internal combustion engine, the number of which varies in different engines, four cylinders arranged side by side and the pistons 11 of which act to drive 5 a single crank shaft 12 being present in the embodiment of my invention illustrated. The upper ends of said cylinders are closed by a single head 13, although a separate head may obviously be provided for each 10 cylinder; and valve mechanism is provided for each cylinder which valve mechanisms are all alike, so that the valve mechanism for one cylinder only need be and will herein-after be described in detail.
- 15 A valve chamber 14 is associated with each engine cylinder and into which a combustible mixture supply passage or conduit 15 leads and through which passage combustible mixture is supplied from a suitable 20 carburetor or equivalent charge forming device not shown, while an exhaust conduit or passage 16 leads from the valve chamber 14 to the external air. The valve chamber of each cylinder is placed in communication 25 with the interior thereof through a port 17, which is connected by or through a passage or conduit 18 with the valve chamber 14; the said passage or chamber being extremely short and in substance a part of the port 30 in the embodiment of my invention illustrated. Heretofore, however, this passage has often been of considerable length in internal combustion engines of the single poppet valve type and has formed a pocket or 35 chamber often of considerable volume; and within which combustible mixture is trapped between the distributing valve and the poppet valve each cycle of operation of the engine, which mixture has heretofore been carried 40 into the exhaust passage upon the exhaust phase of the cycle and wasted.
- 45 Located within the valve chamber is a rotating distributing valve 19 having a recess or chamber 20 adapted as the valve is rotated, at half the speed of the crank shaft as is usual in engines of the type illustrated, to alternately establish a communication between the inlet passage 15 and the common passage 18 and port 17, and between said 50 port and passage and the exhaust passage 16, to thereby provide for the flow of combustible mixture into and of burned gases out from the cylinder through the single port 17.
- 55 The port 17 is itself controlled by a single reciprocating valve 21 which is most usually of the poppet type, and which valve is operated by a cam 22 upon a cam shaft 23 which is driven in any way at half the speed of 60 the crank shaft of the engine. The form of the cam is such that the valve 21 is kept open upon the exhaust and suction or intake strokes of the piston within the cylinder for which the valve in question is provided, and 65 closed upon the compression and working

strokes of the cycle of operation of the engine; and motion is communicated to the said valve through an oscillating lever 24 which is operated by the cam 22 and the free end of which operatively engages the 70 end of the stem 25 of the valve in the form of my invention illustrated; although my invention is in no way dependent upon the particular means employed for operating the poppet valve, and any suitable mechanism may be employed without departing from my invention.

The inlet passages 15 of all the cylinders communicate with and derive their supply of combustible mixture from a single longitudinally extending passage 26 within the head 13, and from a manifold 27 which communicate with a suitable carburetor and discharges into said passage; while all the exhaust passages 16 discharge into a single 85 exhaust manifold 28, as is usual in multiple cylinder internal combustion engines.

Leading into the valve chamber 14 from the external atmosphere is a passage 29 so arranged as to register with the pocket or 90 chamber 20 in the rotating distributing valve and the position of which relative to the ports and passages through which the combustion mixture and exhaust gas flow, and the design of the parts generally, is such 95 that the said inlet passage begins to open by the movement of the forward edge 30 of the distributing valve past the said opening slightly before the rear edge 31 of the said valve contacts with the bridge 32 which 100 separates the inlet passage 15 from the common passage 18; so that there will be a short time during which the passage 18 will be in communication with the inlet passage 15 through the chamber 20 of the distributing valve while the inlet passage 29 is also in communication with the said chamber 20, and a much longer interval during which the passage 18 is cut off by the passing of the edge 31 past the bridge 32, and during 110 which a communication is maintained from the external atmosphere through the passage 29, the chamber 20 and the combustible mixture inlet passage 15, and into the common supply conduit 26 and manifold 27 115 whereby all the cylinders are supplied with combustible mixture.

The purpose of the air inlet passage 29 so arranged as to discharge into the valve chamber or pocket 20 when the said chamber is in communication with the combustible mixture inlet passage 15, but is cut off from the common passage 18 and the exhaust passage 16, is to permit air to be drawn through the passage or conduit thus 120 established, because of the suction effect or reduction of pressure always present in the common supply passage 26 and in the inlet manifold; thus sweeping the combustible mixture out of the said pocket or chamber 125 130

20 and back into the mixture supply passage, and leaving air only in the valve pocket to be discharged therefrom ahead of the exhaust gas when a communication is established between the common passage 18 and the exhaust passage 16, and the poppet 21 is opened.

The arrangement above referred to whereby the common passage 18 is placed in communication with the inlet passage 15 for a short time at the beginning of the scavenging process provided for in my invention is a refinement of less importance in a construction wherein the volume of the said common passage is small, as in the engine herein, than in an engine wherein the equivalent passage is of large volume. The result obtained or effect of such an arrangement of the elements in question is obviously that the combustible mixture trapped within the entire space or passage through which the same flows into the engine cylinder is, upon the closing of the poppet valve 21 and the opening of the air inlet passage 29, drawn back into the inlet passage 15 and manifold 26, 27; thus leaving a negligible amount of combustible mixture, and in fact a quantity closely approaching none at all when the parts are properly designed, to be swept out with the exhaust gas during the exhaust phase of the cycle of operation of the engine and wasted.

It will be appreciated, however, that the loss of combustible mixture will be extremely slight even if provision is not made for the withdrawal of such combustible mixture as is trapped in the common passage 18 as hereinbefore explained; as the form of the poppet valve 21 and the location of the distributing valve is such that the volume of said passage is reduced to a minimum, and the gas trapped within the passage 20 of the distributing valve is entirely removed during the comparatively long time that said passage remains in communication with the combustible mixture inlet passage 15 and with the air inlet passage 29.

Figure 1 shows the parts in the positions which they occupy at the beginning of the suction or intake stroke of the cycle of operation of the engine, the single valve 21 being open and the distributing valve 19 being just about to open up a communication between the inlet passage 15 and the port 17 with which the valve 21 cooperates.

The valve 19 which has been open during the preceding exhaust stroke remains open during the first down or suction stroke of the cycle, at the end of which the parts assume the position shown in Figure 2 with the poppet valve in the phase of closing upon its seat and the distributing valve shutting off communication between the inlet passage and the port 17 and common passage 18.

The valve 21 remains closed during the second or compression stroke of the cycle, and also during the third or working stroke; during which strokes the parts assume the positions shown in Figure 3 at the end of 70 the compression stroke, and the positions shown in Figure 4 at the end of the working stroke.

The distributing valve 19 opens communication with the exhaust passage 16 and the valve 21 opens somewhat before the end of the third or working stroke of the cycle, as shown in Figure 4, as is usual in internal combustion engines; and the poppet valve remains open during the fourth or exhaust 80 stroke and the suction stroke of the next cycle, as will be appreciated.

The design, proportion, and port arrangement of the elements which constitute my invention is such that the exhaust phase of the 85 cycle commences somewhat before the end of the working stroke, and such that the fuel supply passage remains open after the end of the suction stroke, in order to secure a more complete evacuation of the burned 90 gases and a more complete filling of the cylinder prior to the compression stroke, in accordance with common and approved practice in internal combustion engine 95

Shortly after the closing of the valve 21 following the suction stroke the advancing edge 30 of the distributing valve 19 passes the air inlet opening 29, as shown in Figure 6, thus establishing an open passage or communication between the external atmosphere and the inlet passage 15 and longitudinal passage 26, and the interior of the manifold 27, and, inasmuch as there is always a reduced pressure within the manifold and the mixture inlet passage, the establishment of the communication aforesaid will be followed by a flow of air inward through the port or opening 29; which will result in the sweeping of the combustible mixture 110 trapped within the passage or pocket 20 of the distributing valve back into the inlet passage and inlet manifold after the end of the fuel supply phase of the cycle; thus leaving air only in the said pocket or recess to be pushed ahead of the outflowing exhaust gas when the distributing valve shall have moved into the position shown in Figure 4, and upon the opening of the poppet valve 21.

As above explained the arrangement of the parts is preferably such that the common passage 18 remains in communication with the inlet passage 15 for a short time after the valve 21 closes, and during the early 125 part of the phase of the cycle during which the recess 20 of the distributing valve is in communication with the air inlet 29. The result of this feature is that combustible mixture trapped within the passage made 130

up of the recess 20 and the common passage 18 is withdrawn from said common passage, as well as from the pocket in the distributing valve. This, however, is a feature of 5 less importance in cases where the volume of the common passage is reduced to an extremely small amount, as in the engine herein disclosed, than it is in engines wherein the volume of the common passage is large 10 as has heretofore often been the case.

Having thus described and explained my invention, I claim and desire to secure by Letters Patent:

1. In an internal combustion engine of 15 the class described having a cylinder, a piston operating therein, a valve chamber, a combustible mixture inlet passage leading into said chamber, an exhaust passage leading from said chamber, and a port through 20 which a communication is established between said chamber and the interior of the engine cylinder; a reciprocating valve for controlling said port, and the form of 25 which is such that it substantially fills said port when the valve is closed; a rotating distributing valve located within the valve chamber aforesaid and having a chamber adapted to alternately establish a communication between said inlet passage and said 30 port, and between said exhaust passage and said port; and an air inlet passage in said valve chamber and leading into the chamber in said distributing valve, and which inlet

passage is so arranged as to communicate with said chamber at a time when said 35 chamber is in communication with the combustible mixture inlet passage aforesaid.

2. In an internal combustion engine of the class described having a cylinder, a piston operating therein, a valve chamber, a combustible mixture inlet passage leading into 40 said chamber, an exhaust passage leading from said chamber, and a port through which a communication is established between 45 said chamber and the interior of the engine cylinder; a reciprocating valve for controlling said port, and the form of which valve above its seating surface is such that it substantially fills said port when the valve is closed; a rotating distributing valve 50 located within the valve chamber aforesaid and having a chamber adapted to alternately establish a communication between said inlet passage and said port, and between 55 said exhaust passage and said port; and an air inlet passage leading from the external atmosphere into said valve chamber, the arrangement of the elements aforesaid being such that a flow of air may occur from the external atmosphere through said 60 air inlet passage and through the chamber in said distributing valve, and into the said combustible mixture inlet passage.

In testimony whereof I affix my signature.

ROLLIN ABELL.
